UNITED STATES PATENT OFFICE.

JOSEPH BOND, JR., OF PHILADELPHIA, PENNSYLVANIA, ASSIGNOR OF ONE-HALF TO CHARLES M. SWAIN, OF SAME PLACE.

SEWING-MACHINE.

SPECIFICATION forming part of Letters Patent No. 288,765, dated November 20, 1883.

Application filed February 16, 1883. (No model.)

To all whom it may concern:

Be it known that I, JOSEPH BOND, Jr., a citizen of the United States, and a resident of Philadelphia, Pennsylvania, have invented 5 certain Improvements in Sewing Machines, of which the following is a specification.

My invention relates to certain improvements in the sewing-machine for which Letters Patent of the United States No. 245,771 10 were granted to my assignees on the 16th day of August, 1881, the present improvements relating, first, to the device employed for transmitting motion from the upper to the lower shaft of the machine; secondly, to the take-up 15 devices, and, thirdly, to the construction of the spool-case and spool-case holder.

In the accompanying drawings, Figure 1, Sheet 1, is a longitudinal section of the machine with my improvements; Fig. 2, a transverse section on the line 12, Fig. 1; Figs. 3 to 20 6, inclusive, Sheet 2, diagrams illustrating the improved take-up mechanism; Figs. 7 and 8, views of the improved spool-case, and Figs. 9, 10, and 11 views showing the relation of the 25 spool-case to the spool-case holder.

H is the bed of the machine; I I', the stationary arm of the same; J, the driving-shaft; K, the lower shaft for operating the feed-motion and loop-catcher b; B, the needle-bar, 30 and S the presser-bar, all of these parts being constructed and operating in the same manner as in the machine shown and described in the above-named patent.

Crank-pins on the shafts J and K are connected by a rod, D, guided in a grooved plate, L, capable of moving transversely; but instead of securing this plate to a rod adapted to bearings in tubular studs on the opposite sides of the hollow post I' of the arm, as in the patented machine, I form on the back of the plate L a rib, f, which fits snugly, but so as to slide freely, in a groove, g', formed in a transverse bar, g, secured within said hollow post I', this form of guide being simpler and easier to fit 45 up than the rod and tubes formerly used.

The devices for taking up the slack of the needle-thread, after the formation of the loop, are the same in principle as those formerly employed, and comprise the rotating disk L', with 50 hook a, the thread-retainer c, and the eyes d, d', and d"; but in addition to these devices I

now provide the disk L' with a lug, m, which acts on that portion of the thread between the eyes d and d'. This lug commences to act before the hook a has finished taking up the 55 thread, and serves to expedite this operation—that is to say, it insures the rapid taking up of the loop of needle-thread as soon as the latter has passed from the rear of the spool-case. The lug m also serves to impart a certain degree of tension to the thread as the latter is drawn downward, owing to the action of the hook b in forming the next loop, the thread being thereby prevented from slipping off of the hook, and the formation of a perfect loop 60 being insured. (See Figs. 3 to 6.)

The spool-case M which I now use is made of a single block, instead of being in the form of a two-part shell, as before, and in this block is formed a slot, h, for the reception of a spool, 70 N, which can turn freely on a pin, n, adapted to openings in the case, the head of this pin being grooved, so that it can be readily caught hold of and the pin withdrawn when it becomes necessary to remove the spool. 75

Tension is imparted to the thread by passing the same between the end of the spool-case and one of the heads of the spool, as before, a plate, p, bearing against the opposite head of the spool, and this plate being acted upon by 80 a spring, s, under control of a screw, s', as shown in Fig. 8.

The spool-case holder comprises two plates, P and P', the latter being movable, so as to permit of the insertion or removal of the spool-case, which rests in an inclined position, as shown in Fig. 11. Each plate has in front a wing, w, and at the rear a wing, x, and the spool-case is confined longitudinally between these wings, the distance between which, however, is slightly greater than the length of spool-case contained between them, so that a slight longitudinal movement of the spool-case in the holder is permitted. 90

Before the formation of the loop the spool-case rests in contact with the wings w, as shown in Fig. 9; but as soon as the loop is formed over the nose of the spool-case, the tension on the thread causes the said case to move backward in the holder until its rear end strikes 95 the wings x, a clear passage being thus formed for the thread between the front end of the

spool-case and the wings *w*, as shown in Fig. 10. As soon as the loop has passed the center of the spool-case, however, in its backward course, said case again drops down into contact with the wings *w*, and opens a passage for the thread between the rear portion of the spool-case and the wings *x*, as shown in Fig. 9.

The spool-case has three openings, *y*, *y'*, and *y''*, through which the thread passes, and in order to permit the threading up of the spool-case without the necessity of passing the thread through these openings, I form in the casing three slots, *z*, *z'*, and *z''*, each extending from one of the openings to the edge of the case, so that the thread can be readily slipped into the openings.

I claim as my invention—

1. The combination of the shafts *J* and *K*, their crank-pins, and the connecting-rod *D*, with the grooved guide *L*, having a rib, *f*, and the bar *g*, having a groove, *g'*, for the reception of said rib, as set forth.

2. The combination of the take-up device

comprising thread-guides and a rotating hook, *a*, with the lug or projection *m*, acting in connection with said take-up hook, as set forth. 25

3. The combination of the spool-case, the spool *N*, and the pivot-pin *n*, with the tension device comprising the plate *p*, spring *s*, and set-screw *s'*, as set forth. 30

4. The combination of the spool-case *M* with the holder having wings *w* and *x*, located near the opposite ends of the spool-case, and adapted to hold the same in an inclined position, but permitting a slight longitudinal play, whereby 35 the loop is drawn over the spool-case without contact with the wings, as set forth.

5. The spool-case having openings *y*, *y'*, and *y''* and slots *z*, *z'*, and *z''*, as set forth.

In testimony whereof I have signed my name 40 to this specification in the presence of two subscribing witnesses.

JOSEPH BOND, JR.
